VEHICLE SIGNALING DIRECTION APPARATUS

Filed Nov. 8, 1928

UNITED STATES PATENT OFFICE

JOSEPH W. BRENKERT, OF SAN DIEGO, CALIFORNIA

VEHICLE SIGNALING DIRECTION APPARATUS

Application filed November 8, 1928. Serial No. 317,901.

My invention relates to vehicle signaling direction apparatus and the objects of my invention are: first, to provide an apparatus of this class which is adapted to be used for either day or night driving; second, to provide an apparatus of this class in which a source of light mounted in the signaling arm causes portions of each side of the arm to be visible at night; third, to provide an apparatus of this class in which light emitting portions on either side of the signaling arm although receiving light from the same source are caused to emit contrasting colors of light; fourth, to provide an apparatus of this class in which light emitting portions on either side of the signaling arm may be of contrasting color, there being a partition within said arm between said light emitting portions to prevent the light from one light emitting portion from interfering with the light from the other; fifth, to provide an apparatus of this class which is manually operated, thereby insuring its operation; sixth, to provide an apparatus of this class in which the extended end of the arm is provided with a substantially arrow head shaped opening therethrough, which when the arm is held against a semi-illuminated background, such as an ordinary city street at night, light shining through this open portion makes the signaling arm more visible; seventh, to provide an apparatus of this class in which an electric illuminating means is mounted near the base of the signaling arm joined to a tapered tubular portion formed in the arm having light emitting side portions through which the light is reflected forming an indicator means visible at night time, and eighth, to provide a signaling apparatus which is extremely efficient in its action, durable, simple of construction and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the charac-

ters of reference thereon which form a part of this application in which:

Figure 1 is an elevational view of my signaling apparatus with the support therefor shown fragmentarily; Fig. 2 is a sectional view thereof through 2—2 of Fig. 1 with parts and portions shown in elevation to facilitate the illustration; Fig. 3 is a sectional view through 3—3 of Fig. 2 with the signaling arm shown fragmentarily and showing by dotted lines the various shifted positions thereof; and Fig. 4 is an enlarged transverse sectional view through 4—4 of Fig. 2.

Similar characters of reference refer to similar parts and portions throughout the several views of the drawings.

Signaling arm 1, light emitting members 2 and 3, partition member 4, signaling arm support 5, electric light socket 6, electric light 7, electric light reflector 8, casing members 9, 70 housing members 10 and 11, sliding shaft 12, stub shaft 13, bolts 14, and spring 15, constitute the principal parts and portions of my vehicle signaling direction apparatus.

The signaling arm 1 is preferably made of two sheets of material 1^a and 1^b. They both have substantially the outline of an arrow and are held together along the shank portion thereof by bending the one side of each member over the other, as shown in Figs. 1 and 4 of the drawings. The arrowhead portion of the signaling arm formed by the members 1^a and 1^b is provided with an opening 1^c therethrough which is substantially the shape of an arrowhead, as shown in Figs. 1 and 2 of the drawings.

The shank portion of each signaling arm member is provided with a semi-circular depression which becomes reduced in size as it approaches the extended end of the signaling arm and terminates just before the open portion 1^c therein. The semi-circular depression or grooved portion in each signaling arm member form together a substantially conical shaped tubular portion 1^d closed at 95 the one end thereof. This tubular portion 1^d extends to the supported end of the signaling arm.

A longitudinally extending slot 1^e is provided in each side of the tubular portion 100

forming an opening through the signaling arm. Light emitting members 2 and 3 cover each slot 1^e. A partition 4 separates the two halves of the conical tubular portion 1^d and extend to a point just above the slots 1^e therein. This partition member enables the light emitting members 2 and 3 to be of contrasting color and yet be illuminated by the same source of light. The partition member is preferably made of shiny material so as to reflect light cast thereupon outwardly against the light emitting members.

The shank portion of the signaling arm is secured to a bifurcated end 5^a of the signaling arm support 5. Secured between the bifurcated portions 5^a of the signaling arm support 5 is an electric light socket 6 which is adapted to receive an electric light 7, the terminal shank of which, in conjunction with the inner sides of the bifurcated portions 5^a, supports a reflector 8, as shown by dotted lines in Fig. 1 of the drawings.

The light 7 is adjacent to and in line with the open, larger end of the tubular portion 1^d. Thus the light is directed down the tubular portion 1^d and out through the light emitting members 2 and 3 and the slots 1^e. The portions of the tubular portion 1^d above the light emitting members 2 and 3 is preferably coated and made shiny with a refractory material or the light refracting material may be used in the construction of the signaling arm so that this portion will remain shiny and absorb as little of the light as possible before it reaches the light emitting members.

The signaling arm support 5 is secured between a pair of housing members 10 and 11 and is mounted intermediate its ends on a sliding shaft 12, as shown in Figs. 2 and 3 of the drawings. The sliding shaft 12 is supported near its one end in the housing member 11 by means of a bushing portion 11^a formed by extending the housing outwardly along the shaft, as shown in Fig. 2. The opposite end of the sliding shaft 12 is supported by a stub shaft 13 secured to the housing member 10. Space is provided between the two housing members so as to permit arcuate movement of the signaling arm support.

The unsecured end 5^b of the signaling arm support is bent out forming a handle, as shown in Figs. 1, 2 and 3. The base of this handle is adapted to engage notches 11^b provided in the housing member 11 between it and the housing member 10, as shown by the several sets of dotted lines in Fig. 3.

The housing members 10 and 11 are held in spaced relation to each other by means of lugs 11^c extending from the housing member 11. Bolts 14 extending between the housing members 10 and 11 adjacent to these lugs secure said housing members together. A spring 15, coiled around the sliding shaft 12 and hooked at its one end to a bolt

14 and by its other end to a portion of the signaling arm support 5, tends to maintain the signaling arm support in a lowered position, as shown in Fig. 3 of the drawings. Thus, by releasing the handle from the notches 11^b the arm drops to a lowered position. The space between the two housings is large enough to permit the lateral movement necessary to shift the handle member 5^b into and out of engagement with the notches 11^b.

It is obvious that the sliding shaft 12 may be extended and a handle secured thereto so that the apparatus may be mounted on the outside of and operated from the inside of a closed vehicle.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a signaling apparatus, a signaling arm formed of two flat members secured with their flat sides together, a stiffening ridge formed longitudinally in each signaling arm member, said ridges complementing each other and forming therebetween a tapered hollow portion, each of said hollow ridges provided with a longitudinally extending slot therein, a light means adapted to shine within said hollow portion, and light emitting means covering the openings in said hollow portion.

2. In a signaling apparatus, a signaling arm formed of two flat members secured with their flat sides together, a stiffening ridge formed longitudinally in each signaling arm member, said ridges complementing each other and forming therebetween a tapered hollow portion, each of said hollow ridges provided with a longitudinally extending slot therein, a light means adapted to shine within said hollow portion, light emitting means covering the openings in said hollow portion, and a partition mounted between the members of said signaling arm at the junction of the hollow ridges thereof for separating the light rays admitted to said light emitting means from said light means.

3. In a signaling apparatus, a signaling arm formed of two flat members secured with their flat sides together, a stiffening ridge formed longitudinally in each signaling arm member, said ridges complementing each other and forming therebetween a tapered hollow portion, each of said hollow ridges provided with a longitudinally extending slot therein, a light means adapted to shine with-

in said hollow portion, light emitting means covering the openings in said hollow portion, and support means for holding said signaling arm in various shifted positions.

5. In a signaling apparatus, a signaling arm formed of two flat members secured with their flat sides together, a stiffening ridge formed longitudinally in each signaling arm member, said ridges complementing each other and forming therebetween a tapered hollow portion, each of said hollow ridges provided with a longitudinally extending slot therein, a light means adapted to shine within said hollow portion, light emitting means covering the openings in said hollow portion, a partition mounted between the members of said signaling arm at the junction of the hollow ridges thereof for separating the light rays admitted to said light emitting means from said light means, and support means for holding said signaling arm in various shifted positions.

5. In a signaling apparatus, a signaling arm formed of two flat members secured with their flat sides together, a ridge formed longitudinally in each signaling arm member, said ridges complementing each other and forming therebetween a tapered hollow portion, each of said hollow ridges provided with a longitudinally extending slot therein, a light means adapted to shine within said hollow portion, distinctively colored light emitting means covering the openings in said hollow portion, and a partition mounted between the members of said signaling arm at the junction of the hollow ridges thereof for separating the light rays admitted to said light emitting means from said light means.

6. In a signaling apparatus, a signaling arm including a longitudinally extending hollow central portion having a pair of lengthwise extending oppositely disposed elongated slots, an opaque partition member separating said slots, a pair of distinctively colored light emitting members, each positioned over one of said slots, and a common illuminating means for said light emitting members.

7. In a signaling apparatus, a flat elongated substantially rectangular arm terminating at its outer end in a direction indicating arrow head portion, a tubular central portion extending lengthwise with said arm and terminating near said head, and having an elongated slot therein, said arrow head portion having an aperture therein in the form of a direction indicating arrow head and in line with said elongated slot, and means for emitting light from said slot.

In testimony whereof, I have hereunto set my hand at San Diego, California, this 26th day of October, 1928.

JOSEPH W. BRENKERT.
